UNITED STATES PATENT OFFICE.

JOANNES COENRADUS HUBERTUS KRAMERS, OF MAASTRICHT, AND JACOBUS GERARDUS AARTS, OF DONGEN, NEAR BREDA, NETHERLANDS, ASSIGNORS TO WATERGAS-MAATSCHAPPI SYSTEEM DR. KRAMERS & AARTS, OF AMSTERDAM, NETHERLANDS, A COMPANY INCORPORATED ACCORDING TO DUTCH LAW.

APPARATUS FOR THE MANUFACTURE OF WATER-GAS.

SPECIFICATION forming part of Letters Patent No. 785,040, dated March 14, 1905.

Original application filed March 15, 1901, Serial No. 51,503. Divided and this application filed June 26, 1902. Serial No. 113,253.

To all whom it may concern:

Be it known that we, JOANNES COENRADUS HUBERTUS KRAMERS, teacher, residing at 53 Fongerschestraat, Maastricht, and JACOBUS GERARDUS AARTS, manufacturer, residing at Dongen, near Breda, Netherlands, subjects of the Queen of the Netherlands, have invented certain new and useful Improvements in Apparatus for the Manufacture of Water-Gas, of which the following is a specification.

As is well known, water-gas is made by passing steam over red-hot carbon, hydrogen and carbon monoxid being produced. The heat necessary for the production of the water-gas is obtained by the combustion of carbon.

Our invention, which was originally included in our application, filed March 15, 1901, Serial No. 51,503, relates to apparatus by which water-gas of uniform composition may be obtained from any kind of carbon with the smallest possible consumption of carbon, such gas being fitted, in uncarbureted condition, for heating purposes and for incandescence lighting and, when carbureted, as an illuminant.

The apparatus consists of two generators, two regenerators, and a recuperator, as illustrated in the accompanying drawings, in which—

Figure 1 is a front elevation, partly in section, on line I II of Fig. 3. Fig. 2 is a vertical transverse section through one generator and regenerator on line III IV of Fig. 3 and through the economizer on line V VI of Fig. 3. Fig. 3 is a plan, partly in section. Fig. 4 is a sectional elevation, on an enlarged scale, of a distributing device specially applicable to the apparatus; and Fig. 5 is a plan of the central casing thereof.

The generators 1 2 are side by side, and behind each, on a somewhat higher level, is the corresponding regenerator 3 4, with which the generator is in communication. Both regenerators open into the chamber 5, Figs. 1 and 2, between which and the economizer 8 above it is a valve 7, closed or opened by lever

8 and chain 9, Fig. 2. Each generator has a charging-hopper 10 11, kindling-openings 12, and an ash-pit door 13. At suitable positions in the regenerators are provided windows 14. The air-blast enters the economizer by pipe 15, travels round the heating-pipes 16, and issues through the main 17 to feed the generator. This main 17 has two branches 18 19, which enter the generators, respectively, above the fuel therein, and other two branches 20 21, which enter the generators, respectively, below the fire-bars. Valves 22 23 24 25 control these branch pipes, respectively. Steam is supplied through pipes 26, Fig. 2, and is controlled by cocks 27 28. It enters the generator below the fire-bars through pipe 29. The union-pieces 31 32 carry, besides the air and steam pipes, gas-pipes 33 34, Fig. 3, which are controlled by valves 35 36 and conduct the water-gas to the purifiers.

The apparatus is operated as follows: After the hot blow, both generators being in use, with valve 7 and all the air-valves open, the surface of the fuel in one generator—say 1—is covered with coal from the hopper 10. The valve 7 and the air-valves 22 23 24 25 are now closed and the steam-cock 27 is opened, steam being admitted under the fire-bars in generator 1. The steam is thus decomposed and water-gas is produced, which when it arrives at the freshly-added layer of coal has a temperature high enough to gasify the coal partly, so that a mixture of water-gas with heavy and light hydrocarbons is produced. This mixture passes through the regenerators 3 4 and downward through the red-hot fuel in generator 2. Here the hydrocarbons are converted into hydrogen and carbon monoxid and a part of the ammonia is decomposed into nitrogen and hydrogen. The water-gas leaves the generator 2 through the open valve 35 and pipe 34 and passes to the purifiers. When the temperature in the generators and regenerators has fallen too low, the steam-cock 27 and the valve 35 are closed, while the valves 7, 22, 23, 24, 90

and 25 are opened and a hot blow follows. The carbon monoxid formed during this blow is burned at the surface of the fuel by the secondary air admitted through pipes 18 19, the 5 heat thus developed being imparted to the regenerators. The gases, chiefly carbon dioxid and nitrogen, which escape from the regenerators pass into the air through the heating-tubes 16, imparting to these most of their 10 sensible heat. The air blown through pipe 15 travels round the hot tubes 16, and is thus heated before it is delivered to the generators. When it is seen through the windows 14 that the regenerators 3 4 are hot enough, the fuel 15 in generator 2 is covered with fresh coal, and the valves 7 22 23 24 25 having been closed steam is admitted beneath the fire-bars of generator 2. The water-gas produced then passes 20 through the regenerators down through the fuel in generator 1 and away through the opened valve 36 and pipe 33 to the purifiers.

The distributing-valve shown in Figs. 4 and 5 is arranged so that the four valves 22, 23, 24, and 25 are combined in a single four-way 25 cock 37, in the casing of which the main 17 and the branches 18, 19, 20, and 21 terminate. The cock 55 is turned by the lever 38, which moves along the sector 39. When this lever is in its middle position, as shown in Fig. 4, all 30 the air-pipes are in communication with the main 17, but are all cut off therefrom when the lever is turned through an angle of forty-five degrees to the right or to the left. The lever 38 is extended beyond its point of attachment to the axis of the cock, and this end of it is linked by rod 40 to a sliding bar 56, which carries a rod 57, actuating a slide-valve 41 in the valve-chest 42, attached to the cover 43 of the casing of the four-way cock, Fig. 5. To a suitable 35 point of the lever 38 are attached chains 49 50, which pass over pulleys 48 47 and are weighted by weights 51 52. The other ends of these chains are attached to the spring-valves 36 35, respectively, the arrangement being such 40 that the valves do not open until the chain has been pulled up through a certain distance. In the air-supply pipes 18 19 are further valves 45 60 61, graduated to indicate the extent to which they are open for the purpose of accurately adjusting the air-supply above the fuel. The chain 9 by which the valve 7, Fig. 2, between the regenerators and the economizer is actuated is also attached to a suitable point of lever 38, Fig. 4. The operation of this distributing device is as follows: During the hot 50 blow the lever 38 is in its middle position, the air-supply pipes are open, the steam-supply pipes are closed, the gas-valves 35 36 are closed, and the valve 7 is open. For gas-making 55 in the direction from generator 1 to generator 2 the lever is moved to the left, whereupon, first, the air-supply pipes and the valve 7 are closed, then the gas-valve 35 is opened, and by the movement of the steam slide-valve 60 to the right the port 58 is uncovered. Steam

is thus admitted through pipe 45 and union 32 to generator 1. To change from gas-making to hot blow, the lever 38 is moved back into its middle position, whereby the steam-supply is first cut off by slide-valve 41, the 70 gas-valve is next closed, and finally the air-supply pipes and valve 7 are opened. For gas-making in the direction opposite to that first described the lever is moved to the right. The air-supply pipes and valve 7 are first 75 closed, then the gas-valve 36 is opened, and finally the steam is admitted through port 59, pipe 46, and union 32 into generator 2. The valve-chest 42 is provided with a third steam-pipe 53. When the lever 38 is in its middle 80 position—that is, during the hot blow—the steam escapes through port 54 and this pipe 53 to the injector of the boiler. During the gas-making period the blast remains in action, so that a certain pressure is maintained in the 85 air-supply pipes which is about equal to that in the gas-mains and is observed by a monometer. The object of this is that water-gas shall not leak through the valves and form an explosive mixture with the air. 90

In the valve arrangement shown in Figs. 4 and 5 a chain may be attached to the lever 38 and may be connected with the governor of the motor driving the blower, so that the latter may be run at the speed necessary for 95 producing the pressure referred to above during the gas-making.

It is advantageous to fill the hoppers 10 and 11 as soon as they have been emptied, so that the coal may become heated during two periods of hot blow and two periods of gas-making 100 and may enter the generator in a hot condition. In this manner sudden cooling of the red-hot fuel by the admission of the coal is avoided. 105

The height of the column of fuel in this apparatus is not great, so that any kind of fuel may be used—such as coke, hard coal, brown coal, or refuse containing carbon—and combustion to carbon dioxid is possible without 110 great speed of air-blast.

The dimensions of the generators may be small, so that the quantity of nitrogen and carbon dioxid left in the apparatus when the change is made from hot blow to gas-making 115 is proportionately small and the water-gas is only little contaminated by these gases.

When the apparatus is to be applied for the manufacture of semiwater-gas, the hot blow and the regenerators 3 4 are omitted and during the gas-making a mixture of steam and air, instead of steam alone, is blown into the generator in use. The gas produced passes downward through the column of red-hot fuel in the second generator and is then passed 120 successively through an economizer and a preliminary air-heater, finally arriving at the purifiers in a properly-cooled condition. In the economizer the mixture of steam and air 125 is heated before it is admitted to the gener- 130

ator, while the air drawn in by the steam-injector is heated in the preliminary heater before it comes in contact with the steam, the heating being on the counter-current principle. A central four-way cock is also applicable to this modified apparatus.

Having thus described the nature of this invention and the best means we know of carrying the same into practical effect, we claim—

10 1. A gas-producing apparatus comprising a pair of generators, having means on top thereof for supplying fuel, a pair of regenerators arranged in rear of the generators and having their bottom portions connected with the upper portions of the generators by horizontal passages, a passage directly connecting the upper portions of said regenerators, an outlet for products of combustion from said passage, and a valve controlling said outlet, substantially as described.

15 2. A gas-producing apparatus comprising a pair of generators, having means on top thereof for supplying fuel, a pair of regenerators arranged in rear of the generators and having their bottom portions connected with the upper portions of the generators by horizontal passages, a passage directly connecting the upper portions of said regenerators, an outlet-stack connected to said passage, a valve

for controlling the communication between the passage and stack, an air-heating device located in said stack, and pipes leading from the air-heating device to the generators, substantially as described.

3. A gas-producing apparatus comprising a pair of generators arranged side by side, and having means on top thereof for supplying fuel, a pair of regenerators arranged side by side in rear of said generators and at a higher level and having their lower portions connected with the upper portions of the generators, a passage connecting the upper portions of said regenerators, an outlet-stack in communication with said passage, an air-heater located in said stack, an air-pipe leading from said air-heating device, branch pipes leading from said pipe to the generators above and below the grates therein, and means for controlling the passage of air through said branch passages, substantially as described.

In testimony whereof we have hereunto set our hands in presence of two subscribing witnesses.
